MEANS FOR CREATING A MARGINALLY REDUCED REPRODUCTION OF A DESIGN

Owen R. Huggins, South Norwalk, Conn., assignor to Linotone Corporation, a corporation of New York

Application June 3, 1937, Serial No. 146,218

7 Claims. (Cl. 88—24)

This invention relates to photography, and it has for its general object the provision of means for creating a marginally reduced reproduction of a design.

5 In accordance with the present invention, the above as well as other objects are attained by exposing a light sensitive surface to the design or to an image thereof and changing the position of the design or image edgewise a given distance with respect to the position of the sensitized surface. When the sensitized surface is initially exposed a reproduction of the design or image is created thereon in the form of affected and unaffected areas, and as the position of the design 10 or image is changed edgewise the unaffected or light sensitive areas of the reproduction are exposed to only a marginal portion of the design or image, and, in consequence, the size of the unaffected or light sensitive areas is reduced marginally a distance equal to the distance that the design or image is moved edgewise.

For a detailed description of the invention reference may be made to the accompanying drawings wherein;

25 Fig. 1 is a side elevation of a camera employed in practicing the present invention;

Fig. 2 is a rear elevation, partly in section and broken away, of a copy board and its associated mechanism which is also employed in practicing the present invention;

30 Fig. 3 is a side elevation of Fig. 2;

Fig. 4 is a horizontal section taken along line 4—4 of Fig. 3;

Fig. 5 is a vertical section taken along line 35 5—5 of Fig. 2;

Fig. 6 is an enlarged vertical section showing the copy board actuating mechanism;

Fig. 7 is a detail vertical section of the upper eccentric connection between the driving shaft 40 and the copy board;

Fig. 8 is a detail horizontal section taken along line 8—8 of Fig. 6;

Fig. 9 is a detail perspective view of the lower eccentric connection between the driving shaft 45 and the copy board;

Fig. 10 is a diagrammatic view which shows an image of the design moved edgewise in one direction in front of a light sensitive surface to expose the surface to a marginal portion of the design;

50 Fig. 11 is a diagrammatic view which shows the image moved edgewise in the opposite direction to expose the surface to the oppositely disposed marginal portion of the design;

Fig. 12 is a diagrammatic view which shows the 55 image moved edgewise in all directions to expose

the surface to a marginal portion of the design around its entire periphery.

For the purposes of illustration, a design having a number of square elements has been chosen, and in practising the invention as shown diagrammatically in Figs. 10, 11, and 12, a positive 5 22 is prepared having opaque image areas 23 bounded by a light reflecting surface 24. A light sensitive plate 21 is exposed to the positive through a lens 14 and the positive is moved edgewise in its own plane in the direction of the arrow a distance (d) as shown in Fig. 10. When the plate 21 is initially exposed, reproductions of the opaque image areas 23 are created thereon in the form of light sensitive or unaffected areas 25 10 while the remaining area 26 of the exposed plate (shown in full lines in Fig. 10) becomes affected by the light which is reflected back through the lens 14 from the light reflecting surface 24. However, when the positive 22 is shifted edgewise a 15 distance (d) the light sensitive or unaffected areas 25 are exposed to only a marginal portion (m¹) of the opaque image areas 23 and in consequence the width of the reproductions of the design elements as represented by the light sensitive or unaffected areas 25 are reduced marginally a distance (d¹), (shown by the shaded portions in Fig. 10) which corresponds to the distance (d) which the positive is shifted edgewise, this being true since the light reflecting surface 24 of the positive 22 is shifted accordingly. Again, 20 when the positive 22 is shifted edgewise in the opposite direction a distance (d) as shown in Fig. 11, the light sensitive or unaffected areas 25 are exposed to the oppositely disposed marginal portion (m) of the opaque image areas 23 and as a result the width of the reproductions of the design elements as represented by the light sensitive or unaffected areas 25 is further decreased from the opposite edge a distance (d¹). In consequence by progressively shifting the positive 22 25 edgewise in all directions a given distance, or in other words by revolving it without rotation through a path of a given radius in front of the light sensitive surface 21 as shown diagrammatically in Fig. 12 the areas 25 on the plate 21 which remain unaffected are exposed to a marginal portion of the opaque image areas 23 around the entire peripheries thereof, and as a result the reproductions of the design elements as represented by the light sensitive or unaffected areas 30 are reduced marginally in all directions a distance equal to the distance of the edgewise movement of the positive 22.

In the present embodiment of the invention 35

the light sensitive plate 21 is positioned in a holder 28 of what is commonly known as a "process" camera 15. The camera 15 is mounted on an elongated frame 18 and, as usual, it is provided with a lens 14 and a shutter 19. The positive 22 is secured to the front face of a copy board 17 carried by an upright supporting frame 16 which is so disposed on the elongated frame 18 that the positive 22 is positioned parallel with and centrally before the lens 14 and the light sensitive plate 21. The copy board 17 to which the positive 22 is secured is adapted and arranged to be revolved in front of the camera, and to this end it is provided with a back supporting plate 30 as is clearly shown in Figs. 2, 3, 4, and 5.

The plate 30 is connected by means of studs 31 to vertically aligned faces of lugs 32 which project forwardly from the front face of the upright supporting frame 16, and to permit edge-wise movement of the plate 30 and the copy board 17 carried thereby and at the same time maintain the plate 30 flush against the aligned faces of the lugs 32 so that the plate will revolve in its own plane the recesses 33 in which the heads of the studs 31 are positioned and the holes 34 through which the shank portion of the studs extend are enlarged.

As shown more clearly in Figs. 2, 5, 6, and 7 the edge-wise movement of the copy board 17 in all directions is effected by means of a pair of vertically aligned shafts 35 and 36 journaled in bearings 37 and 38, respectively, which are carried by the upper and lower portions of the supporting frame 16. One end of each of the shafts 35 is provided with a drive block 39 which is fixedly secured thereto as by a pin 40, and each drive block is coupled to an eccentric block 41 from which a stud 42 protrudes in eccentric relation with respect to the drive shafts. The stud 40 which protrudes from the upper eccentric block is journaled in a blind anti-friction bearing 43 inserted into the upper central portion of the back plate 30 and the stud which protrudes from the lower eccentric block is journaled in a similar bearing 43a inserted into the lower central portion of the back plate 30. The vertically aligned shafts 35 and 36 are driven from an electric motor 44 mounted on a bearing plate 45 carried by the lower portion of the supporting frame 16, the power from the motor being transmitted to the shafts 35 and 36 through a pair of reducing gears 46, and a pair of associated beveled gears 46a, an angularly disposed shaft 47, a pair of lower beveled gears 48, an upright shaft 49, a pair of upper beveled gears 50, a horizontally disposed shaft 51 and a pair of beveled gears 52. As the vertically aligned shafts 35 and 36 are driven by the electric motor 44, the drive blocks 39, the eccentric blocks 41, and the studs 42 which project therefrom in eccentric relation with respect to the shafts 35 and 36 are rotated accordingly. In consequence, the copy board 17 which carries the anti-friction bearings 43 and 43a in which the ends of the studs 42 are journaled is revolved without rotation or moved without any disturbance in the angles of its horizontal or vertical axes in a circular path having a radius equal to the distance between the studs 42 and the shafts 35 and 36; and as the copy board 17 is so revolved the positive 22 mounted thereon is likewise moved in a similar circular path in front of the lens 14 and the light sensitive plate 21. Under these conditions, as heretofore explained, when the shutter 19 of the camera is open and the plate 21 is exposed, the light sensitive or un-

affected areas 25 which remain on the plate are exposed to a marginal portion of the opaque image areas 23 around the entire peripheries thereof, and, as a result, the reproductions of the design elements are reduced marginally a distance equal to the radius of the circular path through which the positive rotates.

To permit the reproductions of the design elements to be reduced marginally different widths, as may be desired, the eccentric blocks 41 which carry the studs 42 are slidably connected to the drive blocks 39 by a V-shaped tongue and groove arrangement. As shown more clearly in Fig. 6, the lower eccentric block is provided with a micromatic adjusting screw 55 which is threaded through an aperture therein and which is journaled at both ends in bearing plates 56 and 57 carried by the drive block. As shown more clearly in Fig. 7, the upper eccentric block is normally maintained locked to the upper drive block by means of a pair of lock screws 58 and 59 threaded through apertures in plates 60 and 61 carried by the upper drive block. To vary the distance between the centers of the studs 42 and the shafts 35 and 36 the lock screws 58 and 59 are backed off and the shafts 35 and 36 turned until the studs 42 are brought into vertical alignment. The adjusting screw 55 is then turned to change the position of the lower eccentric block on the face of the lower drive block, and as the position of the lower eccentric block is so changed the position of the upper eccentric block on the face of the upper drive block is simultaneously changed a like amount through the medium of the back plate 30 which serves as a connecting link between the two studs journaled therein. After the desired adjustment has been made the lock screws 58 and 59 are then turned into engagement with the upper eccentric block to lock the assembly in position.

By the above described arrangement the reproductions of the design elements may be reduced marginally any given distance but the distance they are so reduced remains constant around the entire peripheries thereof. In accordance with another feature of the invention means are provided whereby uneven marginally reduced reproductions may be obtained, and to this end the copy board 17 is adapted and arranged to be moved edge-wise in opposite directions beyond the limit of the circular path through which it travels as it is revolved by the above described arrangement. As shown more clearly in Figs. 2, 3, and 4, the supporting frame 16 which carries the copy board 17 is movably mounted by means of four rollers 62 to 65 inclusive upon a pair of spaced track members 66 and 67 which extend transversely across the upper side bars of the elongated frame 18, the two front rollers 62 and 63 being journaled on shafts 70 and 71 which project forwardly from the opposite lower front corners of the supporting frame 16 and the two rear rollers 64 and 65 being journaled on shafts 72 and 73 which project rearwardly from the opposite lower rear corners of the supporting frame 16. Movement of the frame 16 to carry the copy board 17 edge-wise is effected by means of a rock shaft 75. This rock shaft 75 is journaled in bracket members 76 and 77 carried by the frame 18 and it is provided at one end with a crank handle 78 and at its central portion with a worm 79 threaded through a boss 80 secured to the underside of the frame 18, the arrangement being such that by turning the shaft 75 in opposite directions by means of the handle 78 the

frame 16 may be moved laterally to and fro as desired. To limit the throw of the handle 78 a pair of adjustable stop blocks 81 and 82 are mounted on a rotatable screw rod 83 on each side 5 and in the arcuate path of a short arm 84 rising from the hub 85 of the handle 78. The screw rod 83 is journaled in bearings 86 and 87 carried by the frame 16, and it is provided with right and left hand threaded sections 88 and 89 with which 10 the blocks 81 and 82 are engaged. At one end the screw rod 83 is provided with a knurled head portion 90 by means of which it may be rotated and at the other end it has an annular groove 91 to receive a guide screw 92 mounted in the bearing 15 86 to prevent endwise displacement of the screw. By rotating the screw rod 83 in opposite directions the stop blocks 81 and 82 are moved simultaneously toward and away from the arm 84, and when the blocks are in contact with the 20 arm as shown in Fig. 3, the rock shaft 75 is locked against movement and the supporting frame 16 is held in its normal or centered position. When, however, the blocks 81 and 82 are moved away from the arm 84, as indicated by dotted lines in 25 Fig. 3, the rock shaft 75 may be turned to shift the frame 16 to and fro. The extent of movement of the frame 16 in either direction may be determined by a micromatrical scale 93 secured to the bracket 94 and arranged to be read in 30 conjunction with a pointer 95 carried by the stop block 82.

To obtain an uneven marginal reduction around the peripheries of the reproductions on the plate 21, the frame 16 is positioned centrally 35 before the camera 15 and the eccentric blocks 41 are adjusted to obtain an even marginal reduction of a desired width in the manner heretofore explained. The copy board 17 is then centered with respect to the lens 14 and the plate 40 21 by adjusting the eccentric blocks 41 until the axis of rotation of the studs 42 are in line with the axis of rotation of the drive shafts 35 and 36 respectively and the frame 16 carrying the copy board 17 is shifted to one side by rotating the 45 rock shaft 75 until the arm 84 banks against the block 81 which has been so set that when the handle 78 banks against it the frame 16 is shifted until the remaining portion of the light sensitive unaffected areas 25 of the light sensitive 50 plate 21 is exposed to a narrower marginal portion of the opaque image areas 23. Thereafter, the rock shaft 75 is turned in the other direction to shift the frame 16 in the other direction until the arm 84 banks against the other stop block 55 82, and as the frame 16 is thus shifted the unaffected or light sensitive areas 25 are exposed to the oppositely disposed marginal portion of the opaque image areas. In consequence, by the arrangement shown and described it is possible to 60 expose the light sensitive or unaffected areas 25 on the plate 21 to a marginal portion of uneven width around the periphery of the opaque image areas 23 on the positive 22, and in so doing create reproductions of the image areas which 65 are reduced accordingly.

From the above description, it is obvious that 70 reproductions reduced marginally any desired distance could be created by properly changing the relationship between the plate 21, the lens 14, and/or the positive 22.

Also, in the present embodiment of the invention, a positive of the design element is specified as being mounted on the copy board, but it is obvious that if a negative of the design is prepared and mounted on the copy board the un-

affected or light sensitive portions of the plate may be exposed to marginal portions of the opaque areas on the negative in the same manner.

Having thus described my invention, I claim:

1. In a photographic machine for creating a marginally reduced reproduction of a design, the combination of a camera, a copy board therefor, a supporting frame for said copy board, a plurality of means for securing said copy board to said frame and adapted to permit limited relative movement therebetween, and means for moving said copy board edgewise in a circular path with respect to said frame and before the lens of the camera.

15 2. In a photographic machine for creating a marginally reduced reproduction of a design, the combination of a camera, a copy board therefor, a supporting frame for said copy board, a plurality of means for securing said copy board to said frame and adapted to permit limited relative movement therebetween, means for moving said copy board edgewise in a circular path with respect to said frame and before the lens of the camera, and means for varying the radius of the 25 circular path through which said copy board is moved.

3. In a photographic machine for creating a marginally reduced reproduction of a design, the combination of a camera, a copy board therefor, a supporting frame for said copy board, a plurality of means for securing said copy board to said frame and adapted to permit limited relative movement therebetween, and an eccentric driving means connected to said copy board and adapted to move the same edgewise in a circular path.

4. In a photographic machine for creating a marginally reduced reproduction of a design, the combination of a camera, a copy board therefor, a supporting frame for said copy board, a plurality of means for securing said copy board to said frame and adapted to permit limited relative movement therebetween, a drive shaft, and eccentric means interposed between said drive shaft and said copy board and adapted to move said copy board edgewise in a circular path in response to the rotation of said drive shaft.

5. In a photographic machine for creating a marginally reduced reproduction of a design, the combination of a camera, a copy board therefor, a supporting frame for said copy board, a plurality of means for securing said copy board to said frame and adapted to permit limited relative movement therebetween, means for moving said copy board edgewise in a circular path with respect to said frame, and means for displacing said frame and copy board laterally a predetermined distance with respect to the position of said camera.

6. In a photographic machine for creating a marginally reduced reproduction of a design, the combination of a camera, a copy board therefor, a supporting frame for said copy board, a plurality of means for securing said copy board to said frame and adapted to permit limited relative movement therebetween, a pair of aligned drive shafts, and an eccentric connection interposed between each of said shafts and said copy board and adapted to move said copy board edgewise in a circular path in response to the rotation of said shafts.

7. In a photographic machine for creating a marginally reduced reproduction of a design, the combination of a camera, a copy board there-

for, a supporting frame for said copy board, a plurality of means for securing said copy board to said frame and adapted to permit limited relative movement therebetween, a pair of aligned drive shafts, an eccentric connection interposed between each of said shafts and said copy board and adapted to move said copy board edgewise

in a circular path in response to the rotation of said shafts, means for adjusting one of said eccentric connections, and means responsive to the operation of said last mentioned means for automatically adjusting the other of said eccentric connections a like amount.

OWEN R. HUGGINS.
